UNITED STATES PATENT OFFICE

2,436,921

DIAL LOCK

Hallan E. Goldstine and Oswin F. Voigt, Port Jefferson Station, N. Y., assignors to Radio Corporation of America, a corporation of Delaware

Application March 22, 1944, Serial No. 527,597

4 Claims. (Cl. 188—83)

1

This invention relates to a new and useful dial lock for use with radio apparatus.

An object of this invention is to provide a self-aligning dial lock having a clamping action such that the spring will have some free motion which will allow the bottom portion to open up.

Another object of this invention is to provide a simple and inexpensive radio tuning dial lock which will tend to keep the lock nut portion from loosening under vibration.

A feature of this invention is a simple spring member which is fastened to a panel by a slotted mounting bar, the spring member being provided with a lock nut and stud which clamps the dial in any desired position.

Some of the advantages of this dial lock over those of the prior art are:

1. It is self-aligning, the clamping action is such that the spring has some free motion and allows the bottom portion to open.

2. It is simple to make and assemble.

3. The clamp has plenty of clearance when open.

4. The knurled nut is under spring action when in the locked position, which tends to keep the nut from loosening under vibration.

5. When assembled the screw stud is peened over, so that the knurled nut cannot fall off.

This invention will best be understood by referring to the accompanying drawing in which:

Fig. 1 is a front elevation of the dial lock,

Fig. 2 is a section taken on line 2—2 of Fig. 1, and

Fig. 3 is a side elevation of Fig. 1.

Referring now to the accompanying drawing, a mounting or support bar 1 is secured to the panel 2 of any suitable radio apparatus (such as a receiver or a transmitter), in any suitable position, by means of two round head screws 3 which are tapped in the panel at 4. The central portion of the mounting bar 1 is provided with a slot 5 around which there is located a spring member 6 which is preferably constructed of beryllium copper or any other suitable spring material. The spring 6 has a flat back portion 6A, a curved front portion 6B, and a dial engaging bent portion 6C which is bent as indicated. A threaded stud 7 having a rectangular bottom plate 8 is arranged to be prevented from rotation by slot 5 and passes through apertures in portions 6A, 6B and 6C of the spring, the location of the apertures being just beyond the position in which a dial plate 9 is arranged to rotate. A knurled thumb nut 10 is mounted for rotation on stud 7 just outside the spring por-

2

tion 6B. The end of the stud 7 is peened over at 11 so that the nut 10 cannot fall off due to vibration and thus become lost. The dial 9 is provided with the tuning operating shaft 12 and knob 13, both of which may be of any suitable size or configuration. The shaft 12 may operate a variable condenser, inductance or similar tuning devices.

In the operation of the device of this invention, whenever it is desired to change the adjustment of the radio apparatus, the knurled nut 10 is loosened by rotating it on the threaded stud 7 which releases the pressure of the spring 6 on the dial plate 9. The desired adjustments are then made by rotating the dial plate 9 and shaft 12 by grasping the handle 13 and rotating the dial until a proper desired setting is obtained on the radio apparatus as indicated by the fixed arrow index shown on panel 2. After the proper adjustment is obtained and it is desired to prevent any further changes in the then obtained adjustment, the knurled thumb nut 10 is then tightened until the curved front open portion of the spring 6 is closed sufficiently toward its rear portion to frictionally engage the dial plate therebetween. The dial plate is thus held in a locked position thereby preventing any further turning of the dial plate 9 and shaft 12.

While we have indicated and described a device of our invention, it will be apparent to one skilled in the art that our invention is by no means limited to the particular device shown and described, but that many modifications may be made without departing from the scope of our invention.

35 What we claim is:

1. An article of manufacture including a support member having a slot and apertures adjacent thereto adapted to receive mounting means, 40 a folded open ended spring located in and around the slot in said support member, a threaded stud passing through apertures in said spring, means located on one end of said stud for engaging the slot in said support member to prevent the turning thereof, and a threaded member positioned on said stud and arranged to close the open ended portion of said spring.

2. A self-aligning dial lock comprising a support plate having a slot and apertures adjacent thereto, means passing through said apertures for mounting said dial lock, a folded open ended spring member secured to said support plate, a threaded stud passing through three aligned apertures in the folded portions of said spring, and 50 a threaded lock nut positioned on said threaded

stud and arranged to close the open ended portion of said spring member whereby said dial is located in a desired position by applying pressure to said spring.

3. A dial lock plate comprising a support member having a slotted portion and apertures therein adapted to receive mounting means, an open ended spring member folded to form three parallel portions, one portion being located in and around said slot, and a threaded stud passing through three aligned apertures in each portion of said spring, a threaded lock nut positioned for rotation on the threads of said stud and arranged to close the open ended portion of said spring member to lock a dial plate in a desired position.

4. A self-aligning dial lock comprising a support member having a slot and apertures adjacent thereto adapted to receive mounting means, a folded open ended spring located in and around the slot in said support member, means located at one end of said stud for engaging the slot in said support member to prevent the turning there-

of, a threaded member positioned on said stud and arranged to close the open ended portion of said spring and means located at the other end of said stud to prevent said threaded member from coming off of said stud.
